UNITED STATES PATENT OFFICE.

ALBERT T. VAN ALSTYN, OF NEW YORK, N. Y.

GARMENT-SUPPORTER.

1,305,418.

Specification of Letters Patent.

Patented June 3, 1919.

Application filed September 17, 1913. Serial No. 790,149.

To all whom it may concern:

Be it known that I, ALBERT T. VAN ALSTYN, a citizen of the United States, residing in New York city, in the county of New York and State of New York, have invented certain new and useful Improvements in Garment-Supporters, of which the following is a specification.

This invention relates to garment-supporters, or hose-supporters, of that class in which the fabric of the hose,—or such other fabric or goods as are to be held in place thereby,—is preliminarily placed or folded over a post or like member which is then placed and held 15 within a clamping-frame that is adapted to be suspended from or connected to the usual supporting band or strap, in a customary manner.

In the accompanying drawing forming a 20 part of this specification, Figure 1 is a side view of a garment-supporter made in accordance with my present invention.

Fig. 2 is a plan view, drawn below and in alignment with Fig. 1, to facilitate comparison therewith.

Fig. 3 is an end view as seen from the right-hand in Fig. 1.

Fig. 4 is a sectional side view, drawn below and in alignment with Figs. 1 and 2, and 30 showing the clamp retracted, while the post is lowered, as when placing or releasing a fabric.

Fig. 5 is a sectional side view showing a 35 fabric in place, and showing the mechanism of the supporter in the closed position illustrated in Figs. 1, 2 and 3.

Fig. 6 is an enlarged plan view of a preferred form of the post member, with the usual fibrous covering omitted.

Fig. 7 is an end view of said form of post member as seen from below in Fig. 6, and Fig. 7^a shows the same post member having modified proportions, whereby to somewhat reduce the otherwise normal dimension 45 or height of the fabric-engaging end of the device.

Fig. 8 is an enlarged view of the right-hand portion of Fig. 5, but with the fabric omitted, while Fig. 9 is a similar view showing the fabric clamped in place.

Similar characters designate like parts in all the views.

For connecting the clamp-frame, as B, of the supporter mechanism, to the usual web or carrying strap, as S, I have shown a well-known form of an ordinary slotted con-

necting-plate, N, (Figs. 1-5) having a bar, 2 for the strap S, a pivot-bar 3 for connecting with the frame B, and the middle-bar 4, for carrying one end of the post-strap T. 60 The member N, however, may be in practice of any suitable or convenient form, proportions and arrangement, since it is not an essential part of my present improvements. For instance, the rearward end 5 of the 65 frame B may be bent or formed over the bar 3 in a well-known manner to form the usual loose or pivotal joint.

As one suitable means for holding and releasing the post or fabric-carrier, as P,— 70 whatever may be the specific form or construction of this member,—I have shown the frame B provided with a preferred form and arrangement of a toggle-action, lever-operated, post-clamping device, as follows: 75 The said frame B, having the two side-bars, as 6, 6' and the end-bar, or clamping abutment, as 7, has near its rearward end a hinge-joint, as 8, (of any well-known or suitable construction), whereby the lever, or lever-plate, as L, is pivotally supported on the frame B; in the present instance, (Fig. 2) this joint 8 is formed as follows: The frame B has a curled portion struck up from said frame which curled portion is located between two lateral curled portions struck up 85 from the lever L, all three curled portions forming a bore with one another to receive the hinge pin. At its forward end the plate or lever L is preferably turned upwardly to 90 form a lip, as at 9, whereby the user may engage the finger, or thumb-nail under the lever-end for operating the toggle-like clamp-ing device.

The lever L is shown provided at a point 95 intermediate of its length, with some suitable hinge-joint, (which may be similar to the joint 8) as indicated at 10, for pivotally connecting with the rearward end of a presser-plate or clamp-member, D; in the 100 present instance, a strip of metal of the lever L is struck up from between the two portions forming the joint 8 and this strip is curled up in the opposite direction to the other two curled portions and positioned intermediate to the curled portions struck up from the presser plate D which three curled portions similar to joint 8 form a bore with one another to receive the hinge pin, the forward end of which is arranged to slide along 105 and between the frame bars 6, 6',—see Figs. 2, 4 and 5. For this latter purpose, the for-

ward end 12 of the clamp or toggle-member D is shown fitted for a sliding engagement with the side-bars 6, 6'; this may be accomplished by making projecting guides or pins, 5 as e, e' on the member D, fitted to slide in grooves as f, f', formed in the inner sides of the bars 6, 6', respectively.

When the clamping device is thus assembled and is in the closed position Fig. 5, the 10 pivot 10 should,—as there shown,—lie below the line from pivot 8 to guide e, so that the lever L on being closed down from its position in Fig. 4, will carry said pivot 10 to a sufficiently low point (Fig. 5) for securing 15 the desired self-locking of the parts in their closed position. Then, by lifting on the point 9 of the lever L, this may be turned back to its position in Fig. 4, thereby first slightly advancing and next drawing back 20 the presser D, and thus releasing any fabric or the like from between the movable clamp-face 12 and the fixed clamp-face 7. In these operations the member D, from e to 10, may be said to constitute one part, or link, of a 25 toggle-joint or linkage device, the other member of which is that part of the lever L which extends from the pivot 8 to the pivot 10; thus the well-known and very effective “toggle-action” is obtained. In practice, the 30 compression of the post-walls r, r', toward each other furnishes a resistance which by its reaction operates to push backwardly on the member D, and thus by the spring-power of the post itself holds the members L and D 35 in their said locked positions as in Fig. 5.

For limiting the backward stroke and retracted position of the lever L and the opening stroke of the clamp-member D, to about the position shown in Fig. 4, and with the 40 thumb-piece 9 in convenient position for use in closing the clamp, while preventing undue strain from being applied to the guide-bearings e, e' I provide some suitable stop device 45 operating directly between said linkage-members L and D. This stop device in the present instance consists of a face on the member D formed by a bend at n, (Fig. 4) in the member D whereby the members D and L engage as stop faces each for the 50 other, when retracted to the desired position, as herein explained. Of course, the stop-faces at n, should be located sufficiently remote from the axis of the joint at 10, to prevent undue strain when the lever L is pushed 55 over to its extreme backward position, as will now be evident.

One object of my present improvements is to provide effective means for properly grasping and holding textile goods of various thickness and texture, and to do this 60 notwithstanding a considerable unevenness in the thickness thereof, and the presence of various folds therein. For these purposes, the member P,—over which the goods are 65 directly placed, and which is usually desig-

nated as the “post,”—is herein shown provided with a resilient side portion combined with a head, as h, which is substantially rigid as against a strain or pressure applied thereto in a direction longitudinally of the sup- 70 porter frame B. This organization of the component parts and features of the post P, is illustrated in a preferred form and arrangement, in the enlarged detail views, Figs. 6, 7 and 7^a, in which the said post is 75 shown formed of a relatively or moderately flexible metal plate, bent into shape and having a mid-portion h, for the post-head, resilient, indented side-forming portions r', r', for the side-walls, and end portions forming 80 base-flanges as t, t', whereby to connect the post P (see Fig. 4) with the supporter-frame-work by a strap, as T, laced through one or more openings as x, x' and y, y' in the plate. The tape or strap T is shown 85 (Fig. 8) extended or folded over the post-head h for thereby supplying a fibrous or similar cover, as c, Figs. 4, 8 and 9 for contacting with the cloth or other fabric,—as F, Figs. 5, 9,—to be held in the supporter. This 90 post-cover c is thus a part of the tape or strap T, and is held in place by the side-cover portions, as c', c'', being extended through the said openings x, x' and y, y', of the post-plate. (See Figs. 1, 4, 5, 8, 9.) 95 This manner of lacing or looping in the strap or connection T serves to cover and bring within this member T, the outer edges of both of the base-flanges t and t'.

In assembling the post-member P, with 100 the frame-work,—as B N,—by means of the combined attaching strap and post-head cover T, this strap after being passed around a retaining bar, as 4, and then passed through the loops or openings in, and over 105 the head of the member P, may then be fastened together at a point, as g, located close to the rearward lower flange, as t, of said member P, for thereby preventing this member from becoming gradually displaced on 110 the strap during the continued use of the mechanism, by the resilient action of the side-walls and of the flanges t, t' of the post-member P.

An important feature of the described 115 post-construction and of the mode of mounting the same, is that the two ends of the post-member, adjacent to the side-bars 6, 6', respectively (see Figs. 2 and 6) operate in a substantially or relatively independent 120 manner, so that if a fabric is thicker,—as by reason of a fold or selvage,—at or near one side of the frame than at the other side thereof, the side portions r and r' of the post-plate will be forced nearer together at 125 such location, without materially reducing the holding power at the other end of the post-member, which thus becomes self-adjusting as to the compressive action of the 130 clamping devices and as to the irregularities

of the fabric. This mode of action is in part provided for by the making of a considerable space, as z , (Figs. 4, 7 and 8) between the side-walls r and r' , whereby the post-plate 5 is made to operate as a resistant spring, as already mentioned. In Fig. 9, said space z is shown considerably reduced, as indicated at z' , by the clamping action of the member D, which is strongly resisted by such resili- 10 ent resistance during the final part of its forward stroke.

Owing to the texture and thickness of such tapes or analogous materials as are desirable for the cover-portion c of the strap T, the 15 use of said slots arranged in pairs about as illustrated, secures an effective retention in proper position of that post-cover, and has the further advantage of making a broad base-portion for the post P, which thus ex- 20 tends forwardly and rearwardly (Figs. 1 and 5) under the clamping faces of the parts 7 and D, for thereby steadyng the post against being deflected or tipped out of its proper position by the pull of the fabric F 25 in the direction of the arrow a' , Figs. 5 and 9. One advantage of the pair of slots x' y' over a single slot in lieu thereof, is that the cover-strap T is thereby readily brought forward into a fold at h , over the 30 extreme forward edge of the flange t' , as well indicated in Figs. 8 and 9.

The manner of applying and using my improved garment or hose supporter, is similar to the way in which other devices in this 35 general class are employed, and will now be evident from the drawing and the foregoing description. When the post P is released and lowered as in Fig. 4, the fabric is placed over the post in the usual manner and the 40 post then pushed up into the frame-opening,—as in Figs. 5 and 9. The lever L is next operated to clamp the post with the fabric, as F thereon, between the jaws or faces of the members 7 and D, thereby hold- 45 ing the fabric between these faces and the

post-cover at c' and c'' , and springing together the compressibly-resilient side walls, r , r' , of the post-plate, as indicated by the narrower distance between these portions in Fig. 9, as compared with Figs. 6 and 8. 50 When any considerable strain is now applied to the fabric F, in the direction of the arrow a' ,—Figs. 5, 9,—the effect is to tend to draw downwardly the post P, as indicated by the arrow a'' , (Fig. 9) and thereby directly increase the gripping action upon the fabric on both sides of the said post-member, and so bring the fabric into a positively gripped condition precluding slipping to any material degree, while holding it with and 60 under a yieldingly-applied pressure that is equally distributed over all the contacting areas of the clamping faces. 55

Having thus described my invention, I 65

claim:
In a garment supporter of the class described, a frame having a post-receiving opening and having operatively supported thereon a post-clamping device comprising a lever pivotally connected at one of its ends 70 to the frame, a presser plate, a portion of said presser plate bent downward, a hinge connection connecting said bent portion to the middle of said lever, said frame having lateral grooves facing one another, a pin secured 75 to the other end of said presser plate below its upper surface and slidably secured in said grooves, the entire arrangement, including the bent portion of said presser plate and the positioning of said pin, coöperating 80 to dispose the upper surface of said presser plate in alinement with the upper surface of said frame and disposing the upper surface of said lever parallel thereto when said presser plate is in clamping position. 85
